SILENCER

Walter H. Powers, Jackson, Mich., assignor to
 Walker Manufacturing Company of Wisconsin,
 Racine, Wis., a corporation of Wisconsin

Application March 24, 1941, Serial No. 384,791

12 Claims. (Cl. 181—54)

The present invention relates to silencers, and in particular is directed to the provision of silencers for automotive service.

The principal objects of the present invention are to provide silencers embodying a primary discharge path, resonator structure associated with the path, and improved means for placing the resonator structure in acoustic communication with the primary path; to provide such structures characterized in that a dynamic or velocity head developed by the gas stream during its flow through the primary path is utilized to drive part of the stream into the resonator structure; to provide such structures characterized in that a conduit forming part of the primary exhaust path opens directly into an otherwise closed resonator chamber, said conduit having an outlet in the side wall thereof through which gases may flow after being subjected to the action of the resonator chamber; to provide silencer structures embodying the aforesaid dynamic tuning features wherein the primary path of gas flow is of the retroverted type; to provide such structures wherein the primary path of gas flow is of the straight-through type; to provide such structures wherein the direct or dynamic tuning feature enables certain economies and simplifications in a manufacturing sense; and to generally improve the construction, arrangement and operation of silencers.

With the above as well as other objects in view, which appear in the following description and in the appended claims, preferred but illustrative embodiments of the invention are shown in the accompanying drawings, throughout the several views of which corresponding reference characters are used to designate corresponding parts and in which:

Figure 1 is a view in longitudinal central section of a silencer embodying the invention;

Fig. 2 is a view in vertical transverse section taken along the line 2—2 of Fig. 1;

Fig. 3 is a view in longitudinal central section of a modified embodiment of the invention;

Fig. 4 is a view in vertical transverse section taken along the line 4—4 of Fig. 3;

Fig. 5 is a view in longitudinal section of a further embodiment of the invention;

Fig. 6 is a view taken along the line 6—6 of Fig. 5;

Fig. 7 is a fragmentary sectional view, illustrating the third gas passage of the embodiment of Figs. 5 and 6;

Fig. 8 is a view in longitudinal central section of a further modification of the invention;

Fig. 18 is a view in longitudinal central section of a further modification of the invention; and

Fig. 19 is a view taken along the line 19—19 of Fig. 18.

It will be appreciated from a complete understanding of the invention that the improvements hereof may be embodied in silencer structures of widely varying constructions, intended for widely differing purposes. By way of illustration of preferred embodiments, the present improvements are herein illustrated in connection with silencers specifically designed for automotive service.

Referring first to the embodiments of Figs. 1 and 2, the silencer comprises an outer shell 38 of elliptical form, having end heads 32 and 34. The head 32 is provided with a neck through which a section of conduit 36 is projected, the outer end of the conduit being adapted for connection to the exhaust pipe (not shown) of the associated engine, and the inner end thereof being connected to the hereinafter described conduit 38. The head 34 is similarly provided with a neck through which a section of conduit 40 is projected, the outer end whereof is adapted for connection to the usual tail pipe (not shown), and the inner end whereof is secured to the herein-after described conduit 42.

The interior of the silencer is provided with silencing structure comprising the previously

mentioned longitudinally extending conduits 38 and 42 and an additional conduit 44, which conduits are supported within the silencer by means of partitions 46, 48, 50, and 52. The partition 46 is perforate, one relatively large opening 54 therethrough being shown, and, with the head 32 and the partition 48, forms a compound resonator chamber 55 within the shell, which communicates with the balance of the silencing structure only through the opening at the end 58 of the conduit 44, which end projects into the just-mentioned resonator chamber and constitutes a tuning neck.

The partitions 48 and 50, together with the connecting portions of the shell 30, define a crossover 58, which provides a gas path between the conduits 44 and 42. The partition 52 and end head 34, in turn, together with the connecting portions of the shell 30, define a crossover 60, which forms a gas path between the righthand ends of the conduits 38 and 44.

In addition, the partitions 50 and 52, together with the connection portions of the shell, define an additional silencing chamber 62, which is in acoustic communication with the interiors of the conduits 38 and 44 through the louvre openings 64 formed in the side walls thereof. The louvre openings 64 may, in the broader aspects of the invention, be variously arranged, but preferably these louvre openings take the tangential form and arrangement described in Gunn Patent No. 1,949,074, which is assigned to the same assignee as the present application.

In accordance with the present invention, also, the conduit 42 is provided, between the partitions 50 and 52, with an intermediate shell 66. The space between the conduit 42 and the shell 66 is divided into two separate chambers 68 and 70 by partitions 72, 74 and 76. The chambers 68 and 70 are isolated from the balance of the silencer structure, except for the acoustic communication between these chambers and the interior of the conduit 42, which is provided by means of the louvre openings 64 provided in the side walls of the conduit 42, and which louvre openings preferably have the form and arrangement of the previously described louvre openings.

It will be noticed that the conduit 44 extends from the crossover 58 through the crossover 60 and terminates in the previously described compound resonator chamber 55. In order to provide communication between the interior of the conduit 44 and the crossover 60, the conduit 44 is provided with a gas outlet within the crossover 60. More specifically, this gas outlet takes the form of a plurality of circumferentially and axially distributed openings 78, which, in the embodiment now being described, preferably have a large enough total area so as to not substantially restrict the flow of gas from the conduit 44 into the crossover 60.

Considering now the operation of the structure of Figs. 1 and 2, it will be appreciated that the exhaust gas stream discharged from the engine into the inlet afforded by the conduit 38, passes to the right along said conduit into the conduit 38. A major component of this gas stream may, by virtue of the velocity head thereof, and by virtue of the restriction afforded by the louvre openings 64 in the side wall of the conduit 38, be expected to pass directly through the conduit 38 into the crossover 60, from whence the gases flow toward the left through the conduit 44. By virtue of the louvre openings 64 in those portions of the conduits 48 and 38, which lie

within the silencing chamber 62, another component may be expected to by-pass the crossover 60, and it is possible, also, that some reverse flow of gases occurs through the louvre openings 64. It is possible, also, that certain parts of the gas stream, which pass out of the conduit 38 or 44 through the corresponding louvre openings, directly re-enter such conduit through such louvre openings.

The pressure pulsations in that component of the gas stream which passes through the chamber 62 are attenuated in part in passing through the louvre openings 64, and in part by the expansion thereof within the relatively large chamber 62. It may be expected, also, that some destructive interference is caused by the rejoinder, in the conduit 44, of the two components, which further attenuates the pressure pulsations of the entire gas stream.

The partially silenced gas stream, which may, for purposes of description, be regarded as made up of a succession of pressure peaks alternating with valleys, develops a substantial velocity head within the conduit 44 and, under the influence of this velocity head, is directed in large part at least past the outlet 78 and thence through the tuning neck 58 into the resonator 55. Each pressure peak entering the resonator 55, of course, builds up the pressure therein and under the influence of this increased pressure, the inflow to the resonator 55 is followed by an outflow of gas therefrom through the tuning neck 58. As will be understood, the return or outflow from the resonator 55 joins a valley in the oncoming gas stream, which rejoinder produces the silencing action which is characteristic of resonator structures.

It will be noted that the conduit 44 may be regarded as having a forcing portion, lying to the right of the outlet 78, and as having a tuning neck portion 58, lying to the left of the outlet 78. The velocity head, which imparts driving force by which the gas stream is driven into the resonator, is built up within the just-mentioned forcing portion and the length of this portion, therefore, determines the degree of this driving force. The length and cross-sectional area of the tuning neck portion 58, on the other hand, in conjunction with the volume of the compound resonator chamber 55, determine the frequency or range of frequencies, which such resonator chamber is effective to silence.

In the present arrangement, the compound resonator chamber 55 is proportioned to attenuate those frequencies which, in automotive practice, are usually referred to as "note"; that is to say, those sounds having frequencies falling, for example, in the range from 40 to 110 cycles per second and certain of the harmonics thereof. The proportioning of the conduit 44 and related elements of the structure are preferably so proportioned that the driving force built up in the forcing portion thereof, is sufficient to drive a substantial part, if not all, of the gas stream past the side outlet 78, thereby subjecting substantially, if not all, of the gas stream to the silencing effect of the resonator 55. This forcing action has been found in practice to very materially increase the effectiveness of resonator structures.

The above-mentioned rejoinder of the outflow from the resonator 55 and the oncoming gas stream occurs in the region of the outlet 78, and the resultant gas stream then passes through the outlet 78 into the crossover 60. From the cross-

over 88, the now substantially silent gas stream passes through the conduit 42 to the silencer outlet 48. Portions of the gas stream passing through the conduit 42 also pass into and out of the small chambers 88 and 108, which, as will be understood, serve to silence what are frequently referred to as the unpitched sounds.

In the modified embodiment of the invention shown in Figs. 3 and 4, the silencer comprises an outer shell 88, having end heads 82 and 84, which enclose the ends of the shell and also accommodate the inlet nipple 88' and the outlet nipple 48'. As before, also, the silencer is provided with a primary gas passage, comprising the conduits 88, 92 and 94, which are supported within the silencer by means of the partitions 88, 98, 108 and 102. The partitions 88 and 98, together with the shell 88 and the head 82, define a compound resonator 104. The partitions 98 and 108, together with the shell, define a crossover 108. The partition 102 and the head 84 cooperate with the shell to define a crossover 102, and the partitions 108 and 102 cooperate with the shell to define an intermediate silencing chamber 110. In this instance, also, the outlet conduit 92 is provided with an intermediate shell 112, which, with the partitions 114, 116, 118 and 120, defines a succession of high frequency or spit chambers, which communicate, respectively, with the interior of the conduit 92 through the louver openings 84. In the instance now being described, the entering conduit 88 is imperforate, but intermediate conduit 94 is provided with louver openings 84, preferably of the previously identified type, which afford acoustic communication between the interior of the conduit 94 and the chamber 110.

The intermediate and outlet conduits are provided, within the crossover 108, with outlets comprising series of circumferentially arranged openings 124 and 128, respectively, which, as in the previous case, preferably have total areas large enough to afford a substantially unrestricted flow of the gas stream.

The outlet conduit 92 is continued directly through the righthand portion of the compound resonator 104 into the lefthand portion thereof, and the same is true of the intermediate conduit 94. The outlet conduit 92 is, however, provided with an enclosing wall or plug 128, which prevents communication through this conduit between the chamber 104 and the crossover 108. The conduit 92 is additionally provided with an outlet comprising a series of openings 130, which are positioned within the righthand portion of the compound resonator chamber 104.

The operation of the embodiment of Figs. 3 and 4 corresponds to that of Figs. 1 and 2, it being noted, however, that the tuning neck between the two parts of the resonator 104, afforded by the lefthand end portion of the conduit 92, alters the frequency or range of frequencies for or over which the resonator is effective.

In the further modified embodiment of Figs. 5, 6 and 7, the silencer comprises a shell 140, having enclosing end heads 142 and 144, which accommodate the inlet 88'' and the outlet 48'', and further comprises a primary gas passage afforded by the longitudinally extending conduits 158, 152 and 154. The just-mentioned conduits are supported within the shell by means of the intermediate partitions 158, 152 and 154. The partition 158 and the end head 48 cooperate with the shell to define a crossover 152 into which the righthand ends of the inlet and intermediate conduits 158 and 152 directly open. The partitions

158 and 152 cooperate with the shell to define a transverse passage or crossover 154 into which the lefthand end of the outlet conduit 154 directly opens. The partition 158 is additionally provided with one or more openings, such as 156, therein which afford communication between the crossover 154 and an expansion chamber 168. The chamber 168, in turn, is defined between the partitions 158 and 160. The partition 158, head 142 and shell 140 define a resonator chamber 161.

Within the chamber 168, the inlet conduit 158 is provided with an intermediate shell 170, which is supported in spaced relation to the conduit 158 by partitions 172 and 174, so as to define a silencing chamber 176. The chamber 176 is in acoustic communication with the interior of the conduit 158 through the louver openings 84 in the walls thereof, and is in acoustic communication with the interior of the chamber 168 through openings 180 in the wall of the intermediate shell 170.

As in the case of Figs. 1 and 2, the open end of the intermediate conduit 152 extends into the resonator chamber 161, and acoustic communication is afforded between the intermediate conduit 152 and the chamber 168 through an outlet constituted by a series of circumferentially arranged openings 182 in the wall of the conduit 152. The openings 182 preferably have a total area sufficient to provide a substantially unrestricted flow therethrough.

In the operation of the embodiment of Figs. 5, 6 and 7, the gas stream entering the inlet passes into the inlet conduit 158 and by virtue of the velocity head thereof, and the restricted sizes of the openings 84 and 158, the major component of this gas stream may be expected to pass directly through the conduit 158 into the crossover 152, from whence it flows into the open righthand end of the intermediate conduit 152. A smaller component of such gas stream passes through the louver openings 84 into the chamber 176 and from thence, through the openings 180, into the intermediate expansion chamber 168. It will be understood that this smaller component of the gas stream is silenced in part at least by its passage through the openings 84 and 158 and through the chamber 176, and is further silenced by the expansion thereof, which results when it enters the enlarged expansion chamber 168.

The component of the gas stream which enters the intermediate conduit 152, by way of the crossover 152, ultimately passes through the outlet 182 into the expansion chamber. As in the case of Fig. 1, however, a substantial part, if not all thereof, initially is driven into the resonator chamber 161, the outflow wherefrom rejoins the oncoming stream in destructive out-of-phase relation, as described above. It will be noticed that the conduit 152 may be regarded as having a forcing portion 152a, lying to the right of the outlet 182, and a tuning neck portion 152b, lying to the left of the outlet 182. As in the case of Fig. 1, the velocity head, which, as aforesaid, imparts driving force by which the gas stream is driven into the resonator, is, of course, built up within the just-mentioned forcing portion 152a of the conduit 152 and the length of this portion, therefore, determines the degree of this driving force. The length of the tuning neck portion 152b, on the other hand, in conjunction with the volume of the resonator chamber 161, determines the frequency or range of frequencies which the chamber 161 is effective to silence. It will be recognized, therefore, that this outlet 182 may be variously positioned along the length of the con-

duit 152 to provide a desirable balance between the frequency for which the resonator 161 is designed and the degree of the driving force, which it is desired to impart to the gas stream.

Continuing with the operation, the gas stream passes through the outlet 182 into the expansion chamber 168 and mingles with the previously described relatively small component of the gas stream. Further silencing results from this mixing by virtue of the different lengths of the paths travelled by the several components.

The gases entering the chamber 168, as aforesaid, pass therefrom through the openings 166 into the crossover 164, from whence they flow through the outlet conduit 154 to the silencer outlet 40.

As in the previous instances, the outlet conduit 154 is provided with a series of high frequency or spit chambers 190, which are defined by the intermediate shell 192 and the indicated partitions. The spit chambers communicate, as will be obvious, with the outlet conduit through the louver openings 84 therein.

Figs. 8, 9 and 10 disclose an embodiment of the invention, which distinguishes from the embodiment of Figs. 1 and 2, in that, among other things, the resonator chamber is interposed in the gas circuit between the inlet and intermediate passes, rather than between the intermediate and outlet passes. Referring particularly to Figs. 8, 9 and 10, the silencer comprises generally a cylindrical shell 200, having enclosing end heads 202 and 204, which accommodate, respectively, the inlet 36 and the outlet 40. The silencing structure within the shell 200 comprises the inlet conduit 210, intermediate conduit 212, and the outlet conduit 214. As before, the inlet and outlet conduits 210 and 214 are, respectively, connected directly to the inlet 36 and the outlet 40.

The interior of the shell is divided, by means of the partitions 216, 218 and 220, into a crossover 222, an intermediate or expansion chamber 224, a second crossover 226, and a resonator chamber 228, into which the righthand end 230 of the inlet conduit 210 extends to provide a tuning neck, as previously described.

Within the crossover 226, the inlet conduit 230 is provided with an outlet comprising a series of circumferentially distributed openings 232 for the previously described purpose, and the total area of which, as before, is preferably such as to provide a substantially unrestricted gas flow. As in the previous instances, it is preferred to place the interiors of the inlet and intermediate conduits 210 and 212 in acoustic communication with the expansion chamber in by-pass relation to the crossover 226. For this purpose, the conduit 210 and its associated intermediate shell 234 are provided with louver openings 84 and 236, respectively, within the chamber 224, and conduit 212 is provided with louver openings 238. The intermediate shell is supported by partitions 239, which cooperate therewith to define an intermediate chamber 241. Also, in order to silence the so-called unpitched sounds, the outlet conduit 214 is provided with a series of small spit chambers 240, which are defined by the associated intermediate shell 242 and the partitions 244.

In the embodiment now being described, the gas circuit extends from the inlet 36, through the inlet conduit 210, the openings 232, the crossover 226, the intermediate conduit 212, the crossover 222, and thence through the outlet conduit

214 and the outlet 40. In view of the acoustic coupling between the expansion chamber 224 and the conduits 210 and 212, it will be appreciated that a portion of the gas stream is enabled to by-pass the crossover 226, the proportioning of the just-mentioned coupling being preferably such that this by-passed component is a minor part of the total gas stream. As in the previous instances, the velocity head of the gas stream within the inlet conduit 210 initially drives a substantial part, if not all, of the stream past the outlet 232 into the resonator chamber 228, thus enabling this chamber to exert a substantial silencing effect.

In a further modified embodiment of Figs. 11 and 12, the arrangement duplicates that described with reference to Figs. 8, 9 and 10, with the exception that the previously described partition 220 is eliminated and a crossover 226' between the inlet conduit 210' and the intermediate conduit 212' is afforded by a member 250, the marginal flange 252 whereof is adapted to be secured to the partition 218'. The member 250 thus acts as a closure or conduit connecting the openings 232' in the conduit 210' with the end of the conduit 212'. The member 250 is provided with an opening, which accommodates the end or tuning neck portion 230' of the conduit 210'.

In the further modified embodiment of the invention shown in Figs. 13, 14, and 15, the arrangement is somewhat similar to that described with reference to Figs. 5, 6, and 7, in that the intermediate pass of the gas circuit is constituted by an enlarged expansion chamber. In Figs. 13, 14, and 15, the shell 260 is provided with enclosing end heads 262 and 264, which accommodate the inlet 36 and the outlet 40. The interior of the shell 260 is provided with an inlet conduit 270 and an exhaust conduit 272. Partitions 274 and 276 act to support the just-mentioned conduits in place, and also serve to divide the interior of the shell into a crossover 278, an expansion chamber 280, and a resonator chamber 282. The chambers 278 and 280 communicate through the partition 274, and for this purpose, this partition is apertured, as indicated at 284. The resonator chamber 282 is isolated from the balance of the silencing structure except for the acoustic connection provided by the open ended tuning neck portion 286 of the conduit 270, which projects into this chamber. The conduit 270 is provided, adjacent the partition 276, with an outlet comprising a series of relatively large openings 290, preferably having a total area sufficient to enable a substantially unrestricted gas flow and is additionally provided with a series of louver openings 292, which are distributed throughout the balance of the length of that portion of the conduit which lies within the chamber 280. As in the previous instances, the outlet conduit 272 is provided with a series of spit chambers 294, defined by the associated intermediate shell 296 and the partitions 298.

The embodiment now being described also illustrates an improved connection between the louver tube 272 and the partitions 274 and 298 associated therewith, which is claimed in applicant's copending application Serial No. 509,263, filed November 6, 1943. As most clearly appears in the enlarged views of Figs. 14A and 14B the louvers 278 in the tube 272 are of the tangential form shown and described in the above identified Gunn Patent No. 1,949,074. These louvers are arranged in axially spaced and circumferentially

offset ring-like rows, the individual louvres in alternate rows being aligned with each other axially of the tube.

The partition 274, and similar comments apply to the partitions 298, is provided with a neck 275 of conical form, the portion of largest diameter thereof being adjacent the junction between the neck and the body of the partition. The diameter of this largest portion is preferably substantially equal to the diameter of the imaginary surface including the crests of the louvres 273. With this relation a relatively snug slip fit is provided between each portion of largest diameter and the tube 272 which enables the partition in question to be fitted over the louvre tube without deforming the individual louvres. This fitting operation, however, causes the individual louvres to deform each neck portion of minimum diameter from its initial circular shape into a polygonal shape, the number of sides of which is equal to the number of louvres in two successive rings of such louvres. The difference between the minimum and maximum diameters is such that this deforming or ironing effect brings the surface of the neck in the region of the small end thereof into contact with or immediately adjacent the body of the tube than would otherwise be the case, and materially facilitates the completion of the connection between each neck and the tube.

It will be noticed that the length of each neck is preferably approximately equal to the spacing, axially of the louvre tube, between two aligned rings of louvers. The final positioning of the partition is preferably such that the neck portion of largest diameter rests upon the louvers in one of such rings, thus bringing the portion of smallest diameter into registry with the other such ring.

The connection between each partition and the louvre tube is preferably made by effecting a series of welds between the tube and the neck portion. Preferably, also, such welds are made adjacent the small end of each neck, and one such weld is made in the space between successive louvers in the corresponding louvre ring. Manufacturing variations may be expected to cause some variation in the exact point at which each such weld is made. In a general sense it has been found that the connection is satisfactory if the welds are made anywhere between the crest of one such engaged louver and the crest of the next successive louver in the same ring. Preferably, and as illustrated in Fig. 14A, however, the welds are made approximately midway between the crest of one such engaged louver and the crest of a louver in the next successive ring of louvers. An additional weld is also preferably made in the region of the rolled seam 272a.

The individual welds form a positive connection between each partition and the tube which secures the two together as a unit, and also serves to minimize any leakage space between the surface of each tube and the neck. Any such leakage spaces which are not eliminated by the welding operations are found to have only a negligible effect, if any, upon the performance of the silencer.

As will be understood, the described arrangement is particularly advantageous because it enables a given louvre tube construction to be utilized in building up a silencer having differing numbers and differing sizes of chambers 294. This is because the individual partitions, such as 75

298, can be secured to the louvre tube at any of a plurality of points along the body thereof.

In operation, it will be understood that the gas stream passes through the inlet 36 into the inlet conduit 270, within which it may be regarded as being divided into two components. The first and relatively small component passes through the louver openings 292 into the intermediate expansion chamber 280. The second and larger component passes the openings 292, and ultimately passes through the outlet 280 into the expansion chamber 280. Under the influence of the velocity head built up within the conduit 270, a substantial part of the second component passes into the resonator chamber 282, which functions in accordance with the previous embodiments. The gas stream passes from the chamber 280 through the aperture 284 into the crossover 278, from whence it flows to the outlet 40 through the outlet conduit 272. As in the previous instances, the small split chambers 284, associated with the outlet conduit 272, serve to silence the relatively high frequency or so-called unpitched sounds not silenced by the previously encountered silencing structure.

In the embodiment of Figs. 16 and 17, the shell 300 is provided with enclosing end heads 302 and 304, which are formed to define the inlet 36 and the outlet 40, respectively. The inlet and outlet are directly connected, respectively, to the inlet conduit 310 and an outlet conduit 312. It will be noticed that the conduits 310 and 312 are directly secured together throughout the intermediate portions thereof, and that these conduits extend through the shell in angled relation, thereby enabling both the inlet and the outlet to be centrally positioned relative to the heads 302 and 304.

A partition 314 gives intermediate support to the inlet and outlet conduits and additionally divides the shell into an expansion chamber 315 and a resonator chamber 318. The end 320 of the conduit 310 extends directly into the resonator chamber 318 and thus constitutes a tuning neck, as in the previous modification.

The chamber 318 constitutes the intermediate pass of the silencer and this chamber is placed in communication with the inlet conduit 310 by means of an outlet, comprising the openings 322 in the conduit 310. In the instance now being described, the lefthand end 323 of the conduit 312 is closed by flattening the same, and this conduit is coupled to the chamber 318 by an outlet comprising the openings 324. As before, the openings 322 and 324 are preferably proportioned to permit a substantially unrestricted flow of gas therethrough. In addition, in order to increase the silencing effect of the expansion chamber 318, the conduits 310 and 312 are provided, throughout their length, with relatively small louver openings 326.

The modification shown in Figs. 18 and 19 is similar to the arrangement of Figs. 16 and 17, with the exception that additional partitions 330 and 332 are provided which, with the adjacent end heads, define, respectively, an expansion chamber 334 at the inlet end of the structure and an expansion chamber 338 at the outlet end thereof. In this embodiment, also, the conduits 310 and 312 are supported in spaced relation to each other by the several partitions.

The operation of the embodiments of Figs. 16 through 19 will, in general, be understood from the previous description of Figs. 13, 14 and 15. Gases entering the inlet conduit divide into two

components, one smaller component passing through the small louver openings 326, and the other and larger component ultimately passing, after being subjected to the action of the resonator chamber, through the outlet 322. The gas stream passes through the intermediate expansion chamber and enters the outlet conduit through the outlet 324, and thence passes directly to the silencer outlet 48'. In particular respect to Figs. 18 and 19, the gas stream is enabled to expand in the chambers 334 and 336, which actions increase the overall silencing effect.

It will be appreciated that from the foregoing description each of the several embodiments of the present invention may be generically characterized in that the primary circuit, which accommodates the flow of the gas stream through the silencer, is arranged to provide structure within which all or part of the gas stream may develop a predetermined velocity head, under the driving force of which a substantial portion of such gas stream is caused to enter a resonator chamber or equivalent structure, whereby the silencing effect of such resonator chamber, for a given size of chamber, is very materially increased. The just-mentioned feature, which is regarded as being of generic character, has been found in practice, particularly in combination with additional silencing structure constructed in accordance with the above-described embodiments, to produce silencers which are exceedingly efficient in operation. Moreover, from a manufacturing standpoint, the present arrangements, wherein in each case a particular section of conduit defines not only a driving or forcing portion but also defines a tuning neck portion, have been found to afford substantial economies and simplifications.

Although only several specific embodiments of the invention have been described in detail, it will be appreciated that various further modifications in the form, number and arrangement of parts may be made without departing from the spirit and scope of the invention.

What is claimed is:

1. A silencer structure comprising an outer shell having an inlet and an outlet and silencing means within the shell, said structure including conduit means within the shell through which gases flow in passing from the inlet to the outlet and within a portion of which said gases develop a velocity head, said structure further including means defining a resonator chamber within the shell into which said conduit means opens and which chamber is closed except for its connection with said conduit means, said velocity head serving to drive at least part of said gases into said chamber, a portion of the wall of said conduit means having at least one opening therein defining a substantially non-restrictive gas outlet in the side thereof external to said chamber but between said chamber and said first mentioned portion, said side outlet communicating with said first mentioned outlet, and said wall portion serving to direct said part of the gases into said chamber.

2. A silencer structure comprising an outer shell having an inlet and an outlet and silencing means within the shell, said structure including conduit means within the shell through which gases flow in passing from the inlet to the outlet and having successive forcing and tuning neck portions, said structure further including means defining a resonator chamber within the

shell into which said tuning neck portion opens and which chamber is closed except for its connection with said tuning neck portion, a portion of the wall of said conduit means having at least one opening therein defining a substantially non-restrictive gas outlet in the side thereof positioned between said portions, said side outlet communicating with said first mentioned outlet, said gases developing a velocity head in said forcing portion which drives at least a part of said gases through said tuning neck portion into said chamber, and said wall portion serving to direct said part of said gases into said chamber.

3. A silencer structure comprising an outer shell having an inlet and an outlet and silencing means within the shell, said structure including conduit means within the shell through which gases flow in passing from the inlet to the outlet and having successive forcing and tuning neck portions, said structure further including means defining a resonator chamber within the shell into which said tuning neck portion opens and which chamber is closed except for its connection with said tuning neck portion, a portion of the wall of said conduit means having at least one opening therein defining a substantially non-restrictive outlet in the side thereof positioned between said portions, said tuning neck being arranged to project into said chamber and being open at said projecting end, said side outlet communicating with said first mentioned outlet, said gases developing a velocity head in said forcing portion which drives at least a part of said gases through said tuning neck portion into said chamber, and said wall portion serving to direct said part of said gases into said chamber.

4. A silencer structure comprising an outer shell having an inlet and an outlet and silencing means within the shell, said structure including conduit means within the shell through which gases flow in passing from the inlet to the outlet and having successive forcing and tuning neck portions, said structure further including means defining a resonator chamber within the shell into which said tuning neck portion opens and which chamber is closed except for its connection with said tuning neck portion, a portion of the wall of said conduit means having at least one opening therein defining a substantially non-restrictive outlet in the side wall thereof positioned between said portions and externally of said chamber, said side outlet communicating with said first mentioned outlet, said gases developing a velocity head in said forcing portion which drives at least a part of said gases through said tuning neck portion into said chamber, and said wall portion serving to direct said part of said gases into said chamber.

5. In a silencer structure comprising an outer shell having an inlet and an outlet and silencing means within the shell, said structure including conduit means within the shell through which gases flow in passing from the inlet to the outlet and having successive forcing and tuning neck portions, said structure further including means defining a resonator chamber within the shell into which said tuning neck portion opens and which chamber is closed except for its connection with said tuning neck portion, a portion of the wall of said conduit means having at least one opening therein defining a substantially non-restrictive outlet in the side wall thereof positioned between said portions, said side outlet communicating with said first mentioned outlet,

said gases developing a velocity head in said forcing portion which drives at least a part of said gases through said tuning neck portion into said chamber and said wall portion serving to direct said part of said gases into said chamber, and said conduit further having a series of restrictive openings in the side wall thereof positioned in the forcing portion thereof.

6. A silencer structure comprising an outer shell having an inlet and an outlet and silencing means within the shell, said structure including a retroverted gas circuit constituted at least in part by a pair of axially overlapping conduits through which gases flow in passing from said inlet to said outlet, one of said conduits having a portion in which said gases develop a velocity head, said structure further including means defining a resonator chamber within the shell into which said one of said conduits opens and which chamber is closed except for its connection with said one conduit, said velocity head serving to drive at least part of said gases into said chamber, a portion of the wall of said one conduit having at least one opening therein defining a substantially non-restrictive outlet in the side thereof externally of said chamber, but between said chamber and said first mentioned portion, said side outlet communicating with said first mentioned outlet, and said wall portion serving to direct said part of the gases into said chamber.

7. A silencer structure comprising an outer shell having an inlet and an outlet and silencing means within the shell, said structure including a retroverted gas circuit constituted at least in part by a pair of axially overlapping conduits, one of said conduits having successive forcing and tuning neck portions, said structure further including means defining a resonator chamber within the shell into which said tuning neck portion opens and which chamber is closed except for its connection with said tuning neck portion, a portion of the wall of said one conduit having at least one opening therein defining a substantially non-restrictive outlet in the side thereof between said portions and externally of said chamber, said side outlet communicating with said first mentioned outlet, said gases developing a velocity head in said forcing portion which drives at least a part of said gases through said tuning neck portion into said chamber, and said wall portion serving to direct said part of said gases into said chamber.

8. A silencer structure comprising an outer shell having an inlet and an outlet and silencing means within the shell, said structure including a retroverted gas circuit having at least two conduits through which gases flow in passing from the inlet to the outlet and a crossover between said conduits, said structure further including means defining a resonator chamber within the shell adjacent said crossover, one of said conduits being extended directly through said crossover and terminating within said resonator chamber, said resonator chamber being closed except for its said connection with said one conduit, and said conduit having a substantially non-restrictive outlet in the side thereof within said crossover, said outlet being defined by a relatively few large openings in the wall of said conduit.

9. A silencer structure comprising an outer shell having an inlet and an outlet and silencing means within the shell, said structure including a retroverted gas circuit having axially overlap-

ping conduits through which gases flow in passing from the inlet to the outlet and an enlarged expansion chamber included in the gas path between two of said conduits, one of said two conduits having successive forcing and tuning neck portions, said structure further including means defining a resonator chamber within the shell into which said tuning neck portion opens, said resonator chamber being closed except for its connection with said one conduit, and a portion of the wall of said one of said two conduits having at least one opening therein defining a substantially non-restrictive outlet in the side thereof within said expansion chamber and between said portions, said side outlet communicating with said first mentioned outlet, said gases developing a velocity head in said forcing portion which drives at least a part of said gases through said tuning neck portion into said chamber and said wall portion serving to direct said part of said gases into said chamber.

10. A silencer structure comprising an outer shell having an inlet and an outlet and silencing means within the shell, said structure including a retroverted gas circuit having at least two axially overlapping conduits through which gases flow in passing from the inlet to the outlet and means defining a crossover forming a gas path between said two conduits, said structure further including means defining a resonator chamber within the shell into which one of said conduits directly opens and which is closed except for its connection with said one conduit, and said one of said conduits extending through said crossover into said chamber and having a substantially non-restrictive outlet in the side thereof within said crossover, said outlet being defined by a relatively few large openings in the wall of said conduit.

11. A silencer structure comprising an outer shell having an inlet and an outlet and silencing means within the shell, said structure including a retroverted gas circuit through which gases flow in passing from the inlet to the outlet comprising an inlet conduit, an outlet conduit and an enlarged expansion chamber constituting an intermediate pass of said circuit, said structure further including means defining a resonator chamber within the shell into which one of said conduits directly opens and which resonator chamber is closed except for its connection with said one conduit, said one conduit having a substantially non-restrictive outlet in the side thereof positioned within said expansion chamber and said one conduit further having a series of relatively restricted openings which open into said expansion chamber.

12. In a silencer provided with an inlet and an outlet, a conduit forming part of a retroverted gas circuit through which gases flow in passing from the inlet to the outlet, means defining a crossover forming a gas path between said conduit and another part of said circuit, means defining a resonator chamber, said conduit being arranged to extend through said crossover to said resonator chamber and having an outlet which directly opens into said resonator chamber, and said conduit having a substantially non-restrictive outlet in the side wall thereof positioned within said crossover, said outlet being defined by a relatively few large openings in the wall of said conduit.

WALTER H. POWERS.

CERTIFICATE OF CORRECTION.

Patent No. 2,357,791.

September 5, 1944.

WALTER H. POWERS.

It is hereby certified that error appears in the printed specification of the above numbered patent requiring correction as follows: Page 6, second column, line 48, claim 4, for the word "turning" read --tuning--; page 6, second column, line 60, claim 5, for "In a silencer" read --A silencer--; and that the said Letters Patent should be read with this correction therein that the same may conform to the record of the case in the Patent Office.

Signed and sealed this 31st day of October, A. D. 1944.

Leslie Frazer
